(57) **CLAIM**

We claim the ornamental design for a tool handle, as shown and described.

DESCRIPTION

FIG. 1 is a front, lower, right perspective view of one embodiment of the claimed design;

FIG. 2 is a front, upper, right perspective view of the embodiment of FIG. 1;

FIG. 3 is a rear, upper, left perspective view of the embodiment of FIG. 1;

FIG. 4 is a right side elevation view of the embodiment of FIG. 1;

FIG. 5 is a front view of the embodiment of FIG. 1;

FIG. 6 is a left side elevation view of the embodiment of FIG. 1;

FIG. 7 is a rear view of the embodiment of FIG. 1; and,

FIG. 8 is a bottom view of the embodiment of FIG. 1.

Areas of the drawings shown within the broken lines are directed to features of the tool handle that form no part of the claim. The broken lines in the drawings are for illustrative purposes only and form no part of the claimed design.

While the accompanying drawings illustrate one or more exemplary embodiments, it should be understood that according to other exemplary embodiments that should be considered to be within the possession of the inventors of the present application at the time this application is being filed and at its earliest priority date, it is contemplated that any illustrated solid lines (or portions thereof) may be converted to broken lines and that any illustrated broken lines (or portions thereof) may be converted to solid lines so as to claim or disclaim portions, components, or sub-components of the designs shown. It is further contemplated that shading may be added or removed to claim or disclaim the corresponding surfaces.
